UNITED STATES PATENT OFFICE.

MICHAEL W. NEUENS, OF PORT WASHINGTON, WISCONSIN, ASSIGNOR TO WESTERN IMPLEMENT COMPANY, OF PORT WASHINGTON, WISCONSIN.

GRINDER.

1,162,304.

Specification of Letters Patent. Patented Nov. 30, 1915.

Application filed February 13, 1915. Serial No. 7,992.

To all whom it may concern:

Be it known that I, MICHAEL W. NEUENS, a citizen of the United States, and resident of Port Washington, in the county of Ozaukee and State of Wisconsin, have invented 5 certain new and useful Improvements in Grinders; and I do hereby declare that the following is a full, clear, and exact description thereof.

10 My invention has for its object to provide a simple, durable and effective power-driven grinder unit, primarily comprising a pulley-carried arbor that is mounted upon a bowed strut provided with means adapted to receive a series of interchangeable supports embodying a sickle-bar clamping means, a pulverizer-disk clamping means and a tool rest or support, whereby sickles, tools of various types and pulverizer disks may be 15 sharpened without the assistance of a skilled grinder.

With the above objects in view the invention consists in certain details of construction and combination of mechanical elements as hereinafter set forth with reference 20 to the accompanying illustrations and subsequently claimed.

In the drawings Figure 1 represents an elevation of a power grinder embodying the 25 features of my invention equipped with an attachment for supporting and grinding the blades of a sickle-bar, parts being broken away and in section to show certain novel features in detail; Fig. 2, a detailed cross-section through the sickle-bar supporting mechanism, the section being indicated by line 2—2 of Fig. 1; Fig. 3, a detailed sectional view through one end of the arbor showing the means for attaching the sickle-bar grinder wheel, the section being indicated by line 3—3 of Fig. 1; Fig. 4, a detailed sectional view through the sickle-bar attaching mechanism, the section being indicated by line 4—4 of Fig. 2; Fig. 5, a fragmentary sectional elevation of one end of the grinder unit having attached thereto a pulverizer disk-supporting means, which means is interchangeably fitted to the grinder unit with relation to the sickle-bar supporting 40 means; Fig. 6, a detailed elevation of the head end of the disk-supporting means with parts broken away and in section, and Fig. 7, a sectional elevation through the grinder unit, the section being indicated by line 7—7 of Fig. 1, showing an adjustable tool-

rest, which rest is associated with a universal grinder-wheel that is adapted to be fitted to the juxtaposed arbor end.

Referring by characters to the drawings, 1 represents a base block, to which is bolted the base stretch 2 of a channel iron bowed strut having upwardly extending arms 2', the said channel-iron being U-shaped in cross-section. The upper open ends of the strut arms receive depending ears 3 of a pair of alined journal boxes 4, the said box ears being secured to the arms by bolts 3'. Mounted in the journal-boxes is an arbor 5 provided with thrust-resisting collars 5' which abut the inner faces of the companion journal-boxes, the said arbor being also provided with a drive pulley 5" that is designed to be placed in belt connection with a source of power, especially of the small gas engine type, such as used about farms for various purposes. The base-block, which carries the arbor-supporting strut, is arranged to be firmly anchored to a fixed support or bench by bolts 1', it being also understood that, in some instances, this block 20 may be dispensed with, in which case the strut is secured to a metallic skeleton frame by bolts 1'', which bolts, as shown, are utilized for clamping the base block and base stretch of the strut together. Both ends of the arbor are slightly reduced for the reception of clamping collars 6, 6', between which fittings various grinder-wheels are clamped by nuts 7 that are in threaded union with the ends of said arbor. As shown in Fig. 1, 25 the arbor is fitted with only one grinder-wheel A, the face of which grinder-wheel is beveled in opposite directions from the central point for the especial purpose of sharpening sickle-bar blades.

The arms 2' of the arbor-supporting strut are also provided with alined apertures 8 through which, as shown in Fig. 1, there is fitted a guide-rod 9, the rear end of which guide-rod is provided with a head 8', whereby end thrust with relation to the arm socket is resisted in one direction. End thrust of the guide-rod 9 in the opposite direction is opposed by a split key 8'', which is fitted through an aperture that is formed in the rod. The outer end 9'' of the rod extends beyond the arm struts, as shown. Oscillatorily mounted upon the guide-rod 9 are the legs 10 of a yoke member, the base-bar 10' of which has secured thereto a ma-

95

100

105

110

nipulating handle 10''. Both of the yoke-arms 10 are adapted to have sliding play upon the guide-rod 9 and one of said arms is positioned to move back and forth between the strut arms 2', while the opposite arm is adapted to have similar movement about the projecting end 9'' of the guide-rod. The yoke-arms are also connected by a pintle-rod 11, which pintle-rod has 10 hingedly mounted thereon leg portions 12 of a sickle-bar gripping bracket, the said legs being cross-connected by a reach-strap 12', as best shown in Fig. 1. Each gripping bracket leg 12 is formed with a cutter-bar socket 13, into which is registered the cutter-bar α carrying sickle-knives B and one of said bracket legs has extending therefrom a rest-lug 13', whereby the sickle mechanism is more conveniently alined. When the 20 sickle-bar mechanism is affixed to the bracket legs it is clamped thereto by gripping fingers 14 which engage certain of the knives B. These gripping fingers are provided with jawed ends 14', which are seated 25 over the ends of the bracket-legs and said fingers are firmly confined by clamping bolts 15, which pass through the same and suitable apertures formed in the ends of the legs, the said bolts being secured by thumb-nuts 15', as best shown in Figs. 1 and 2. The sickle-bar and knives, when thus clamped, are laterally adjusted upon the 30 guide-rod 9, whereby their opposite cutting faces are centered upon the beveled faces 35 of the grinding wheel A, as shown in Fig. 1.

A grinding pressure between the wheel and blades is effected by a tension spring 16, which tension spring connects one of the arms 13 of the bracket and a lug 17' of a 40 toe bracket 17, the latter being secured to the juxtaposed yoke-arm 10 by a bolt 17''. Oscillatory movement of the toe bracket is opposed by a lip 17''', which lip overlaps the upper edge of the yoke arm. The toe 45 bracket 17 is also provided with a projecting stop-lug 18, which lug is adapted to receive an adjustable stop-bolt 18'', the same being in threaded union with a web that connects the bracket leg and strap portion 50 12' thereof.

From the foregoing description it is manifest that, when the sickle-bar supporting mechanism is put into operation, the proper bevel for sharpening the converging 55 cutting edges of the blades is automatically insured, due to the taper upon the abrading wheel and the blades are thus effectually sharpened by imparting an oscillatory movement to the yoke. After the opposite 60 pair of cutting edges of one set of blades have been properly ground, the sickle-bar gripping bracket is shifted longitudinally so as to aline the center of the abrading wheel A with the interstice between the succeeding 65 pair of blades, whereby they will be

properly ground and so on throughout the series. It is also manifest that, after the cutting surfaces have been reground between a set of blades that are positioned intermediate of the bracket legs 12, the gripping fingers are loosened to permit adjustment of the sickle-bar backward or forward, whereby a second series of blades are positioned between the bracket-legs for the purpose of subjecting their cutting edges to 75 the grinding operation as previously mentioned. 70

If it is desired to grind the cutting edges of a series of pulverizer disks, the sickle-bar equipment or mechanism is removed from the grinder unit, the dismantling operation being effected by simply removing the cutter-pin 8'. Thereafter the guide-rod is withdrawn from its position of rest within the strut aperture and, coincident to this 80 movement, the cutter-bar supporting mechanism is freed, whereby it can be removed. A disk supporting mechanism is then attached to one of the strut arms. This disk supporting mechanism comprises a slotted 85 base leg 19 having a foot 19', which foot is alined with the strut arm aperture 8. A clamping bolt 20 is then fitted through the foot and arm aperture and is confined by a clamping nut 20'. Thus the slotted base-leg 90 is firmly secured to the strut and projecting beyond one end of the arbor. 95

Adjustably secured to the slotted base-leg 19 is a slotted leg section 21, the said leg members being clamped together by a suitable bolt 22 and winged clamping nut 22', the bolt being passed through the slots of both leg sections. The upper end of the leg section 21 terminates with a box 23, into which is oscillatorily fitted the shank 24 of 100 a head 24', the said shank being confined by a split key 25. The head is bored at a right angle to its shank portion 24 for the reception of a stud 26, the outer end of the same being formed with a collar 26' and a projecting threaded pin 27. The stud is arranged to revolve within the head and is held against end play by a split-pin 26'', as shown. This stud is adapted to receive any 105 type of disk C such as are usually employed 110 in connection with farm implements. These disks are centrally apertured and the aperture is fitted over the stud-pin 27, whereby the disk is seated upon the collar 26'. Thereafter the disk is confined by a collar 115 29 which is dropped over the pin 27 and said collar is drawn tightly against the inner face of the disk by a clamping nut 29', which nut is in threaded union with the pin 27. 120

In order to provide the proper bevel for 125 sharpening the disk C, the juxtaposed end of the arbor 5 is fitted with a grinding wheel A', which grinding-wheel is substituted for the grinding-wheel shown in Fig. 1. This disk grinding-wheel A' is formed with a 130

portion of its face upon a plane paralleling the axis of the arbor, while the outer portion or disk grinding surface is suitably tapered.

- 5 From the foregoing description it will be seen that a disk of any diameter and concavity can be readily adjusted so as to cause the edge to be sharpened to be properly seated with relation to the beveled portion 10 of the grinding-wheel and after this adjustment is effected the clamping nut 22' is tightened, whereby the disk is firmly supported in its selected position with relation to the grinder. Thereafter motion being imparted to the spindle, it is obvious 15 that the proper bevel will be presented for grinding the renewed cutting edge, the oscillatory head permitting the disk to compensate coincident to a regrinding operation.
- 20 Referring to Fig. 7 of the drawings, the rear end of the arbor is shown in said figure equipped with a universal grinder wheel D, which wheel is adapted to grind tools or implements of various kinds. It is desirable 25 in ordinary grinding of this character to provide means for supporting the tools being ground and, with this in view I provide an L-shaped supporting bar 20, the base section 30' of which is slotted and adapted to 30 receive an anchor-bolt 31, which anchor-bolt, as shown in Figs. 1 and 7, is extended up through the base-block 1. The vertical reach of the tool-supporting bar 30 has riveted thereto an angle-iron cross-strut 32, 35 upon which strut the tool to be ground is adapted to rest, whereby the proper angle with relation to the stone or grinding wheel can be maintained. It is also obvious that, owing to the means of connecting this supporting bar with the base, the said supporting bar can be adjusted laterally, whereby 40 the cross-strut is adjusted back and forth with relation to the periphery of the wheel D.

I claim:

- 45 1. A power grinder comprising a substantially upright U-shaped strut, arbor journals detachably seated in the ends of the arms of the strut, an arbor mounted in the journals, a holder support detachably connected 50 to and extending transversely through and projecting laterally beyond the arms of the strut below the arbor, and tool holders mounted on and adjustable longitudinally of the support.
- 55 2. A power grinder comprising a strut

formed of channel iron, the strut being bent to a substantially U-shape to provide an elongated base and upstanding end arms, the strut being disposed so that at its base the side flanges are pendent and at its arms, 60 the flanges project outwardly, the ends of the arms form sockets that are open at their free ends and on their outer sides, means engaging the base of the strut to hold the pendent flanges thereof in engagement with 65 a support, arbor journals having ears that enter the socket seats, an arbor mounted in the journals, a tool-supporting holder having an adjustable engagement with the lower portion of the strut. 70

3. A tool grinder comprising a strut formed of channel iron shaped to form an elongated base and disposed so that the pendent side flanges thereof will engage a base support, the ends of the channel iron 75 being bent upward to form arms that are open at their outer sides, the free ends of the arms forming seats for journals, and the lower portions of the arms being provided with alined openings for the reception of 80 tool holder supports.

4. A tool grinder comprising a strut formed of a continuous strip of channel iron, shaped to provide a flat elongated base having upstanding arms at the ends thereof, 85 the channel formation of the arms providing seats for the reception of journals, and the lower portions of the arms being provided with means for the reception of tool holder supports. 90

5. A power grinder comprising a strut composed of a channel-iron strip that is U-shaped in cross-section and bent upwardly at its ends to form arms, the ends of the arms forming seats that are closed on three 95 sides, journal-boxes having pendent portions extended into said seats, means for fastening said pendent portions in said seats, a grinder carrying arbor mounted in the journal-boxes, and means for imparting power 100 to said arbor.

In testimony that I claim the foregoing I have hereunto set my hand at Port Washington in the county of Ozaukee and State of Wisconsin in the presence of two witnesses. 105
